CLAIM

We claim the ornamental design for an augmented reality pack, as shown and described.

DESCRIPTION

FIG. 1 is a front right perspective view of a new design for an augmented reality pack.

FIG. 2 is a top perspective of a new design for an augmented reality pack.

FIG. 3 is a rear right perspective view of a new design for an augmented reality pack.

FIG. 4 is a top view of a new design for an augmented reality pack.

FIG. 5 is a left side view of a new design for an augmented reality pack.

FIG. 6 is a front view of a new design for an augmented reality pack.

FIG. 7 is a right side view of a new design for an augmented reality pack.

FIG. 8 is a rear view of a new design for an augmented reality pack; and,

FIG. 9 is a bottom view of a new design for an augmented reality pack.

The broken lines in the drawings depict portions of the augmented reality pack and form no part of the claimed design.

1 Claim, 9 Drawing Sheets
